DRAFT RIGGING

Norman B. Akitt, Rochester, N. Y., assignor to
The Symington Company, New York, N. Y., a
corporation of Maryland

Application July 19, 1928, Serial No. 293,999

10 Claims. (Cl. 213—69)

This invention relates to railway draft rigging and more particularly to the connection between couplers and yokes whereby angling of said couplers in all directions upon the application of draft and buffing forces is permitted.

The principal object of my invention generally considered is to provide a simplified connection between the coupler and yoke in railway draft rigging whereby horizontal and vertical angling of said coupler is permitted at all times without the use of additional or more complicated elements than those ordinarily employed.

Another object of my invention is to provide a swivel butt coupler construction in which the shank of the coupler is provided with a clearance slot for a horizontal connecting key, said key being formed with a concave bearing notch in the rear edge and the butt of the shank being formed with a vertical spool portion, the front

20 half of said spool contacting the notch in the key for permitting horizontal angling of the coupler on draft and the rear half contacting a concave bearing portion formed on or disposed forwardly of the associated front follower.

25 A further object of my invention is to provide a coupler and yoke connection permitting angling therebetween, said connection involving a horizontal draft key extending through registering slots in said coupler and yoke, the rear edge of

30 said key having a curved bearing notch engaged by a cooperatively curved spool portion on the coupler permitting horizontal angling of said coupler, vertical angling thereof being permitted by the clearance between the ends of the key and the slots in the yoke receiving said key, a front follower being disposed rearwardly of said coupler butt and formed with a concave bearing portion engaging the rear portion of the spool of the coupler butt whereby angling of said coupler is permitted, not only upon the application of draft forces but also under the action of buffing forces.

35 A still further object of my invention is the provision of a swivel butt coupler as previously referred to, in which the connecting key between said coupler and yoke is prevented from undesired removal by a vertical pin disposed forwardly thereof and partially closing the slot in the coupler, sufficient clearance, however, being provided

40 to permit the desired angling of said key with respect to said coupler.

An additional object of my invention is to provide a key for connecting a coupler and yoke and permitting angling therebetween, which key is formed with rearwardly flaring top and bottom faces for providing increased bearing area between said key and the butt of the associate coupler.

45 Other objects and advantages of the invention relating to the particular arrangement and con-

struction of the various parts will become apparent as the description proceeds.

Referring to the drawings illustrating my invention, the sketch whereof is defined in the appended claims:

50 Figure 1 is a horizontal sectional view on the line 1—1 of Figure 2, looking in the direction of the arrows and illustrating the portion of railway draft rigging embodying my invention.

55 Figure 2 is a vertical sectional view on the line 2—2 of Figure 1 looking in the direction of the arrows.

60 Figures 3 and 4 are views corresponding respectively to Figures 1 and 2 but showing a modification.

65 Figure 5 is a front elevation of a front follower such as shown in Figures 3 and 4 but slightly modified.

70 Figure 6 is a side elevation of the follower shown in Figure 5 with the front bearing portion or block detached therefrom.

75 Referring to the drawings in detail, like parts being designated by like reference characters, and first considering the embodiment of my invention illustrated in Figures 1 and 2, a portion of railway draft rigging is disclosed involving a coupler 1 with a rearwardly extending shank portion 2 formed with a slot 3 receiving a horizontal key 4 operatively connecting said coupler 1 with the associated yoke 5. Although said yoke is shown as of a vertical type with upper and lower arms 6 and 7 joined at their forward portions by side webs or walls 8, slotted at 9 for receiving the ends of the key 4, I do not wish to be limited to a vertical yoke.

80 The slot 3 in the coupler stem 2 is formed sufficiently long to permit the assembly of the key 4 therein, said key, it will be noted, being of special form in that it has a concave bearing notch 10 in the rear edge thereof which notch normally receives the vertical, preferably cylindrical, spool portion 11 comprising the butt of the coupler shank 2. The spool has a preferably uniform curvature corresponding with and complementary to the curvature of the bearing notch 10 in the key so that horizontal angling between said stem or shank and key is permitted, as will be understood.

85 On account of the rearward extensions 12 on the key defining the curved notch therein a relatively long slot 3 is necessary in the coupler shank for permitting insertion of said key. In order, however, to prevent undesired removal of

90 said key 4 from the shank a retainer is provided, which in the present embodiment takes the form of a vertical pin 13 headed at its upper end and passing through the slotted portion of the shank to the coupler, so as to restrict the length of said slot, and cooperate with the rearward extensions 12 in preventing undesired removal of the key, while at

the same time leaving sufficient clearance for permitting the desired angling between said key and coupler shank. The pin 13 may be retained in proper position in any desired manner as by 5 means of a cotter 14 extending through a corresponding aperture in the lower end thereof.

In order to effectively transmit draft forces from the butt of the coupler 1 to the associated cushioning mechanism illustrated diagrammatically by dot and dash lines at 15 a front follower 16 is provided between the butt or spool portion 11 of the coupler and said cushioning mechanism. Formed on the front face of said follower 16 is a forward projection 17 formed with 10 a front bearing notch or pocket 18 concavely curved to correspond with the curvature of the coupler spool portion 11. Although said extension providing the bearing on the front of the follower 16 is shown integral with said follower, I 15 do not wish to be limited to said showing as, if desired, it may be formed separate from and connected thereto in any desired manner as illustrated in Figures 5 and 6 to be described hereinafter.

20 Although the spool portion 11 on the coupler stem preferably has uniform curvature on its front and rear portions yet the curvature of the rear portion may be different from, or less than that of the front portion, if desired, in accordance 25 with Figures 3 and 4. Although the curvature of the spool portion 11 and the corresponding bearing pocket 18 on the follower extension 17 are shown cylindrical thereby providing for horizontal angling only between the parts yet, if desired, 30 it may be formed spherical as illustrated in Figures 3 and 4, to be hereinafter described, whereby universal angling between the coupler butt and said follower upon the application of buffing forces is permitted.

35 The operation of my aforescribed draft rigging is as follows: Upon the application of draft forces the said forces are transmitted from the spool portion 11 of the coupler through the key 4 to the yoke 5 and from there through the cushioning mechanism 15 to ordinary or desired front draft lugs (not shown) on the center or draft sills (not shown) of the car. The butt of the coupler pulls away from the bearing pocket on 40 the front of the follower 16 so that the necessary angling of the coupler takes place only between the engaged front portion of the spool 11 and the rear curved edge 10 of the key 4. Vertical angling on draft is permitted by the clearance 45 between the key 4 and the slots 9 in the sides 8 of the yoke, said key angling on its front edge in 50 the slots 9 of the yoke.

55 Upon the application of buffing forces such forces are transmitted directly from the butt of the coupler to the front follower 16 and through the cushioning mechanism to the rear follower and rear draft lugs (not shown) or any other means for transmitting such forces to the associated draft sills (not shown) of the car. As the cushioning mechanism 15 is compressed the engagement between the coupler spool 11 and the key 4 is broken and said coupler is permitted to 60 angle with respect to the abutting front follower extension 17.

65 Although only horizontal angling is especially provided for, vertical angling may be permitted to a slight extent by rocking of the front follower 16 or rocking on the extension thereof or, as previously mentioned, the engaging surfaces between the parts may be made spherical as illustrated in Figures 3 and 4.

Referring now to the embodiment of my invention illustrated in Figures 3 and 4, the construction as here disclosed is very similar to that of Figures 1 and 2, except that provision is made especially for universal angling of the 80 coupler in all directions under the influence of both draft and buffing forces. The coupler 1a, as in the previous embodiment, has a shank 2a slotted at 3a for receiving a draft key 4a for connecting said coupler to the yoke 5a. As in the previous embodiment, said draft key 4a passes through slots 9a in the yoke and is retained in position by a pin 13a.

85 The rear edge of the key 4a is formed with a bearing notch 10a receiving the vertical spool portion 11a of the coupler butt and thereby permitting horizontal angling between said coupler and key.

90 In order to increase the bearing area between the key and spool portion 11a without greatly increasing the weight of the key, said key is preferably formed tapering or provided with rearwardly diverging upper and lower walls so that it is thicker adjacent its rear edge than adjacent its forward edge. The associated follower 100 16a is, as in the previous embodiment, formed with a forward extension 17a, the front face of which has a concave spherical pocket 18a receiving the correspondingly curved butt portion 19a of the coupler. The curvature of the rear portion 19a is preferably less than that of the forward portion, whereby the effective bearing 105 area is increased, and the diameter is maintained greater, or at least not less than the greater transverse dimension of the coupler stem, 110 in this instance the height. In order to facilitate vertical angling between the parts the slots 9a in the yoke are formed with sufficient clearance with respect to the ends of the key 4a so 115 that they do not interfere with a limited amount of vertical angling which may be desired. The mechanism here described operates the same as that shown in Figures 1 and 2, except that angling on the application of buffing forces is freely 120 permitted both vertically and horizontally, due to the spherical curvature of the coupler butt and bearing pocket of the front follower.

125 Referring now to the modification of my invention as illustrated in Figures 5 and 6, a front follower 16b is illustrated which may be used instead of the follower 16a of the previous embodiment, said follower, instead of having an integral extension thereon, has a separable bearing member 17b, the front of which is recessed to provide a concave spherical bearing pocket 130 18b for receiving the butt of an associated coupler as in the previous embodiment.

135 The separable extension 17b may be connected to the front face of the follower 16b in any desired manner as by means of integrally tapering pins 21 received with a driving fit in corresponding pockets 22 in the front face of the follower 16b. Otherwise the construction of the follower and associated parts may correspond with that of the previous embodiment.

140 From the foregoing disclosure it will be seen that I have provided a swivel butt coupler in which horizontal swivelling is permitted by the special formation of the shank butt and connecting draft key between said shank and the 145 associated yoke; vertical swivelling on draft being permitted by clearance between the ends of the key and the yoke slots and swivelling on buff being permitted by the engagement of the coupler butt in a pocket formed on the front of 150

the associated follower which alternatively freely permits horizontal or universal angling of said coupler.

I claim:

5 1. In railway draft rigging, in combination, a coupler with a rearwardly extending shank, the butt of said shank being formed with a vertical spool portion, a yoke, a horizontal draft key extending through registering slots in the shank 80
10 of said coupler and said yoke, said key being notched and the front half of the spool portion on the coupler shank contacting the notched portion of the key, and a front follower engaging the rear portion of said spool and formed 85
15 with a concave bearing portion curved to correspond with the curvature of the spool.

2. In railway draft rigging, in combination, a coupler, a yoke, said coupler and yoke being formed with registering slots, a key extending 90
20 through said slots for connecting said coupler and yoke, said key having a curved rear edge engaged by a correspondingly curved portion on the coupler for permitting angling therebetween, said key increasing in thickness from the front 95
25 to the rear edge to increase the bearing area between it and said coupler.

3. In railway draft rigging, in combination, a coupler, a yoke, a key generally flat on both sides connecting said coupler and yoke by passing 100
30 through registering slots therein, the rear edge of said key having a curved bearing notch and the engaged portion of the coupler being cooperatively curved for permitting horizontal angling of the coupler on the application of draft 105
35 forces, vertical angling of said coupler on draft being permitted by the front of the key pivoting in the yoke slots, and means connected to the coupler to assist the engaging notch and coupler surfaces for preventing undesired removal of the 110
40 key.

4. In railway draft rigging, in combination, a coupler with a rearwardly extending shank, the butt of said shank being formed with a vertical spool portion, a yoke, a horizontal draft key extending through registering slots in the shank 115
45 of said coupler and said yoke, said key being notched and the front half of the spool portion on the coupler shank contacting the notched portion of the key, and a front follower engaging the rear portion of said spool and formed with a concave bearing portion curved to correspond with the curvature of rear portion of the spool, the rear portion of the spool being of decreased 120
50 curvature for increasing the bearing area with respect to the follower.

5. In railway draft rigging, in combination, a coupler, a yoke, a key connecting said coupler and yoke, the engaging surfaces of said coupler and key being curved to permit angling therebetween in the plane of said key on draft, a generally flat front follower disposed between the arms of said yoke rearwardly of said coupler, said follower being provided with a detachable front bearing portion curved in both directions and the butt of the coupler being correspondingly curved and engaging said bearing portion whereby universal angling of the coupler on the application of buffing forces is permitted.

6. In railway draft rigging, in combination, a coupler with a rearwardly extending shank, the butt of said shank being formed with a vertical 125
70

spool portion, a yoke, a horizontal draft key extending through registering slots in the shank of said coupler and said yoke, said key being integral and formed with a concavely curved bearing notch in the rear edge thereof, the front part of the spool portion of the coupler shank being convexly curved to correspond with the curvature of the notch and normally nesting therewith to allow angling of the coupler directly about said key, and a front follower with a curved front face engaging a correspondingly curved rear portion of said spool for transmitting buffing forces from the coupler to associated cushioning mechanism.

7. In railway draft rigging, in combination, a coupler, a yoke, a key generally flat on both sides connecting said coupler and yoke, said coupler and key having engaging surfaces shaped so as to provide for angling between said coupler and yoke, and means disposed in front of said key and extending through said coupler to assist the engaging surfaces in holding said key in place.

8. In railway draft rigging, in combination, a coupler, a yoke, a horizontal key generally flat on both sides connecting said coupler and yoke, 100
45 said coupler and key having engaging surfaces curved to permit angling therebetween, said key extending through a slot in said coupler with sufficient clearance to permit said angling, and a vertical pin partially closing said slot after 105
50 positioning of said key to assist the engaging surfaces in preventing undesired removal of the latter.

9. In railway draft rigging, in combination, a coupler with a rearwardly extending shank, the butt of which is formed with a vertical spool portion, a hooded vertical yoke, a horizontal key connecting said coupler and yoke, said key having a concave notch in its rear edge and the front part of the spool portion being correspondingly 110
55 curved and normally fitting in said notch to allow the coupler to angle with respect to said key, a front follower disposed between the arms of said yoke rearwardly of said coupler, said follower having a forward projection fitting between the 115
60 side walls of the hooded portion of said yoke, the front portion of said projection being curved substantially spherical, and the rear part of the spool portion of the coupler correspondingly curved to provide for universal angling thereof 120
65 with respect to said follower.

10. In railway draft rigging, a coupler having a horizontal slot with the portions above and below said slot joined by a bearing portion defining the rear end of said slot, said bearing 125
70 portion comprising a forwardly facing convex protuberance, a yoke having arms with slots therein registering with said coupler slot, an integral draft key passing through all of said slots to connect said coupler and yoke, the coupler slot providing sufficient clearance for angling with respect to said key, said key having rearward projections extending on either side of said bearing portion and defining a concave notch normally seating on said protuberance to provide for horizontal angling of said coupler, and means for partially closing said coupler slot and cooperating with said extensions on said key 130
75 in preventing undesired removal thereof.

NORMAN B. AKITT.
